UNITED STATES PATENT OFFICE.

LOUIS H. AYER, OF CHICAGO, ILLINOIS.

BONDING PIN.

Application filed February 26, 1923. Serial No. 621,154.

My invention relates to bonding pins such as are used for attaching electrical conductors to rails, and has reference particularly to a bonding pin whereby a number of electrical conductors may be simultaneously secured to the rail by means of the same pin.

Tapered bonding pins are commonly employed for connecting electrical conductors to rails, such pins being formed with one or more longitudinal grooves in which the conductor is clamped by wedging engagement of the pin in an aperture of the rail. These pins are usually circular in cross section so that a substantially uniform compressing strain is imposed on the pin as it is driven into the aperture of the rail, and in order to hold the conductor firmly in the groove, it is customary to form the latter so that a substantial portion of the conductor is exposed for direct wedging engagement with the aperture of the rail. This, however, results in a considerable mutilation or stripping back of the conductor which is of a comparatively soft material and not only reduces the conducting capacity but also increases the liability of breakage.

The principal objects of my invention are to provide a multiple groove bonding pin wherein excessive stripping back or mutilation of the conductors is avoided; to localize the compressing strain on the pin so that it is effective at opposite sides of each groove and tends to close the portions of the bonding pin at each side of the groove over the exposed portion of the conductor; and in general, to provide an improved bonding pin for securing a number of conductors simultaneously to a rail.

On the drawings:

Fig. 1 is an enlarged side view of a double groove bonding pin constructed in accordance with my invention;

Fig. 2 a view looking at the smaller end of the bonding pin shown in Fig. 1;

Fig. 3 a view partly in section showing the manner of connecting rails with my improved bonding pin;

Fig. 4 an enlarged view on the line 5—5 of Fig. 3, showing the bonding pin in position preparatory to being driven into the rail aperture;

Fig. 5 a similar view showing the bonding pin driven into place;

Fig. 6 an enlarged sectional view on the line 6—6 of Fig. 3;

Fig. 7 a view similar to Fig. 2 showing my invention embodied in a bonding pin having three wire grooves; and

Fig. 8 a similar view showing the bonding pin provided with four wire grooves.

Referring to the drawings, the numerals 1—1 indicate two adjoining rails, 2—2 conductors for connecting the two rails and 3—3 apertures in the rails in which the ends of the conductors 2 are to be secured. The bonding pin is indicated as a whole at 4 and is tapered at one end as indicated at 5, to facilitate insertion in the aperture 3 of the rail. A pair of grooves 6—6 extend from end to end of the pin and at opposite sides thereof to receive the conductors 2, and the portion 7 of the pin beyond the tapered portion 5 is also tapered but more gradually than the portion 5, in order to afford a driving fit in the aperture 3, whereby the pin is not only secured in the aperture but also caused to clamp the conductors 2 in the grooves 6.

The taper of the portion 5 of the pin may be of ordinary conical formation, that is, of such a form that all sections thereof are circular in form, but the portion 7 is of a special tapered form to effect a more substantial clamping or gripping of the conductors 2 in the grooves 6 and also to avoid unnecessary mutilation of the wire. To this end the portion 7 is not tapered in the mid-plane A—A of the grooves 6 but is of a uniform thickness, substantially the same or a trifle greater than the diameter of the rail aperture 3 in which it is to be inserted, but the pin is of oval or elliptical cross-section and tapered in the plane B—B at right angles to the mid-plane of the grooves 6, the portions at opposite sides of the plane A—A being formed about divergent axes so that the portion 7 is not only formed with a gradual longitudinal taper but the taper thereof increases with the circumferential distance from the grooves 6—6 to points at right angles to the mid-plane A—A so that maximum taper is in the plane B—B.

With this construction there is practically no wedge action on the pin in the plane A—A of the grooves 6 but merely a snug fit, the grooves 6 being parallel and uniformly spaced from the plane B—B so that the conductors 2 when seated in the grooves 6 are substantially parallel. The grooves 6 are also of such depth that only a small portion

of the conductors 2 are exposed for engagement with the rail aperture, such engagement being provided to afford a scraping action between the conductors and the edge of 5 the rail aperture to clean the surfaces and insure a good electrical connection between the conductors and the rail but not a peeling or shearing action. Owing to the parallel arrangement of the conductors in the bonding pin, however, wedge action between the 10 conductors and the rail is substantially obviated and excessive mutilation of the conductors avoided.

With the construction described, when the 15 conductors are laid in the grooves 6 and the pin driven into the rail aperture 3, the compressing strain of the wedge engagement is exerted in a direction crosswise of the grooves 6 and only a snug fit occurs between the pin 20 and the conductors and rail aperture in the mid-plane A—A of the grooves, thereby affording relief for the compressing strain in circumferential directions at each side of the plane B—B of maximum compressing strain. 25 This results in a slight crowding of the opposite grooved sides of the pin against the corresponding opposite sides of the aperture 2 sufficient to hold the conductors 3 firmly against the rail aperture and also 30 causes the lips or outer extremities of the side walls of the grooves to fold over the exposed portions of the conductors 3 substantially as shown in Fig. 5, so that the conductors are clamped down in the grooves 6 and 35 firmly engaged at all points therearound by the pin 4 excepting at the portions of their surfaces where contact is had between their conductors and the rail.

A perfect electrical connection is thus afforded as well as a substantial mechanical 40 connection without the excessive mutilation or peeling back of the conductors which occurred in previous bonding pin structures, and, moreover, the capacity of the conductor is practically unimpaired and liability of 45 breakage reduced to a minimum.

In Figs. 7 and 8 I have shown modified forms of bonding pins constructed in accordance with the invention just described but 50 arranged with three and four grooves respectively for connecting a corresponding number of conductors to the rail. The grooves 8 in these modified forms are parallel and have a suitable depth so that the conductors 9 are only slightly exposed for scraping engagement with the rail aperture as in 55 the structure hereinbefore described, said pins of Figs. 7 and 8 being substantially untapered excepting between the grooves. To 60 this end the portions between the grooves are formed on divergent axes so that said portions are characterized by an arcuate bulge which gradually increases from end to end 65 of the pin, and this affords a maximum compressing strain midway between the grooves

as in the structure of Figs. 1 to 6 inclusive, and results in the folding of the side lips of the grooves over the conductors so that the conductors are securely clamped in the bonding pin, the latter locked in the rail aperture 70 and sufficient contact permitted between the conductors and the rail aperture to afford the proper electrical connection.

While I have shown and described my invention in a preferred form, I am aware that 75 various changes and modifications may be made without departing from the principles of my invention, the scope of which is to be determined by the appended claims.

I claim as my invention :

1. An electrical connector comprising a pin having a plurality of longitudinal grooves, said pin being of the same radius throughout the major portion of its length on the planes bisecting the respective grooves on the 80 grooved side of the pin and being provided with a circumferential bulge between the grooves and extending lengthwise of the pin, said bulge having the axis thereof divergently arranged with respect to the longitudinal 85 axis of the pin.

2. An electrical connector consisting of a pin having a plurality of parallel longitudinally extending grooves, said pin being of uniform diameter a major portion of its 90 length on the planes bisecting the grooves on the grooved side of the pin and provided with an arcuate enlargement between the grooves extending lengthwise thereof, said enlargement being formed about an axis which is divergently arranged relatively to the longitudinal axis of the pin.

3. An electrical connector consisting of a pin having a plurality of longitudinal grooves, said pin being untapered in the mid-plane of each groove on the grooved side of the pin and having a tapered form gradually increasing from each groove to a point midway between it and the adjoining groove or 105 grooves.

4. An electrical connector comprising a pin having a plurality of longitudinal grooves, the diameter of said pin at any point in a major portion of its length and on any of the planes bisecting the respective grooves being 110 the same on the grooved side of the pin, and said pin being of increasing diameter from end to end of such major portion in planes passing through portions of the pin located between the grooves thereby centering all 115 compressing strain, when the pin is driven, between the grooves.

5. An electrical connector comprising a pin having a plurality of longitudinal grooves, the radial dimension of said pin at any point 120 in a major portion of its length and on any of the planes bisecting the respective grooves being the same on the grooved side of the pin, and said pin being of increasing radial dimension from end to end of such major por- 125 130

tion in planes passing in the portions of the pin located between the grooves thereby centering all compressing strain, when the pin is driven, at a plurality of spaced points on the 5 periphery of the pin between the grooves.

6. An electrical connector comprising a pin having a plurality of longitudinal grooves, the radial dimension of said pin at any point in a major portion of its length and on any 10 of the planes bisecting the respective grooves being the same on the grooved side of the pin, and said pin being of increasing radial dimension from end to end of such major portion in planes passing in the portions of the pin located between the grooves thereby centering all compressing strain, when the pin is driven, between the grooves at a plurality of spaced points on the periphery of the pin. 15

7. A bonding pin formed with three or 20 more grooves therein for the wires, the diameters of the pin being constant through a major portion of the length of the pin from end to end when taken on planes bisecting the grooves on the grooved side of the pin, and

gradually increasing on planes passing between the grooves. 25

8. A bonding pin having a plurality of longitudinal grooves of a depth less than a radius at any point, said pin having a tapered entrance end and tapering to a less degree 30 between said end and the head at a plurality of longitudinal points between the grooves and gradually increasing in taper circumferentially from the side of each groove to a point midway between a pair of grooves, the 35 portions of the pin between the sides of the grooves beyond the tapered entrance end and in planes bisecting said grooves being untapered and continuously uniformly spaced from the axis of the pin along the lengths of 40 the grooves, whereby opposite sides of the pin at each groove are compressed around a conductor inserted therein when the pin is driven into a rail aperture, in conformity with the surface of the conductor, whereby peeling or 45 shearing of the conductor at the edge of the rail aperture is prevented.

LOUIS H. AYER.
